G. H. WHEARY.
TRUNK COLLAR CONSTRUCTION.
APPLICATION FILED JUNE 8, 1914.

Patented Nov. 30, 1915.

UNITED STATES PATENT OFFICE.

GEORGE HENRY WHEARY, OF RACINE, WISCONSIN.

TRUNK-COLLAR CONSTRUCTION.

1,162,715.

Specification of Letters Patent. Patented Nov. 30, 1915.

Application filed June 8, 1914. Serial No. 843,690.

To all whom it may concern:

Be it known that I, GEORGE H. WHEARY, a citizen of the United States, and resident of Racine, in the county of Racine and State 5 of Wisconsin, have invented new and useful Improvements in Trunk-Collar Construction, of which the following is a description, reference being had to the accompanying drawings, which are a part of this specification.

This invention relates to improvements in trunk collar construction and more particularly (although not solely) to that type of trunk known as a wardrobe trunk. 15 Trunks of this type are usually divided vertically medially into two sections which are hinged together and are adapted to be swung laterally to open position to gain access to the interior of the sections. In 20 trunks of this type one of the sections is usually divided into drawer and other compartments and the other section is usually adapted to hold the wardrobe and is usually provided with rails and garment hangers. 25 Trunks of this type are suspended thereon which may be drawn from the section while suspended on the rails. The wardrobe section is usually open at its upper end and is provided with a top cover which is hinged to the wardrobe section or to the drawer section. As the open 30 end of the section naturally weakens the end construction of the section, the top covers are constructed to overlap the upper edge, or what is known, in the nomenclature 35 of the art, as the collar. This collar is usually secured to the inner upper edge portions of the section and projects upwardly from the three sides of the section and is overlapped by the side flanges of the cover 40 which abut against the upper edges proper of the trunk section when the cover is in closed position. The side flanges of the cover are also provided with a depending strip of material which overlaps the side 45 edges proper of the said section. Heretofore this collar has been formed of strips of wood glued and riveted to the upper edge portions of the wardrobe section and the garment hanger tracks have in turn been 50 connected to a reinforcing band which was fastened to the collar by rivets or screws. This construction is comparatively very expensive to manufacture and does not possess the strength desired as the light strips of wood are weakened by the considerable 55 number of rivets extending therethrough.

Furthermore, the construction described materially increases the weight of the trunk and is also bulky in size and thereby lessens the capacity of the trunk.

It is one of the objects of the present invention to overcome the before mentioned objectionable features and provide a trunk collar construction which is of simple construction, is strong and durable and is well 60 adapted for the purpose desired.

A further object of the invention is to provide a trunk collar construction in which the improved collar also serves the function of a reinforcing means for the upper end 70 portion of the trunk and eliminates the use of a separate reinforcing means.

A further object of the invention is to provide a trunk collar formed of metal to which the garment hanger tracks may be 75 directly connected thereby forming a strong connection well able to withstand the hard usage trunks are ordinarily subjected to.

A further object of the invention is to provide a trunk collar construction which is 80 particularly adapted to support garment hanger tracks of either the removable type or of the fixed type.

With the above and other objects in view, the invention consists of the improved trunk 85 collar construction and its parts and combinations as set forth in the claims, and all equivalents thereof.

In the accompanying drawing in which the same reference characters indicate the 90 same parts in all of the views: Figure 1 is a top view of a wardrobe section of a wardrobe trunk provided with the improved collar construction, a portion of the drawer section of the trunk being indicated by 95 dotted lines; Fig. 2 is a vertical sectional detail view thereof taken on line 2-2 of Fig. 1; and Fig. 3 is a top detail view of a portion of the wardrobe section having a modified form of hanger track connected 100 thereto.

Referring to the drawing the numeral 5 indicates the trunk body generally which is divided centrally vertically to form a body portion 6 and a wardrobe section 7 105 hinged thereto and arranged to be swung horizontally to open position. The upper end of the wardrobe section is open as indicated by the numeral 8 and is covered by a top cover 9 which is hinged to the upper 110 front edge of the body section 6 and swings over the wardrobe section when the ward-

robe section is in closed position. The top cover is provided with depending front and side flanged portions 9, the lower edge portions of which abut against and rest upon 5 the upper edge portions 10 of the wardrobe section. The depending flanges are provided with a strip of material 11 along its lower edge portion which overlaps the upper edge portion of the wardrobe section 10 when the said section is in closed position and the cover is swung thereover.

A collar 12 formed of a strip of metal or of material of greater strength than the material of the trunk walls is connected to the 15 inner edge portion of the upper open end of the wardrobe section and projects upwardly therefrom a sufficient distance to form comparatively a wide collar which is overlapped by the side flanges of the top cover when 20 the cover is in closed position. The collar is of approximately U-shape to conform to the contour of the wardrobe section and is firmly riveted to the upper edge portion of the said section. A strip of material 13 is 25 interposed between the collar and the trunk section to offset the collar inwardly and provide clearance space between the said collar 12 and the side flanges 9 of the cover to accommodate the heads of rivets or other 30 connected parts extending through the said cover.

Garment hanger tracks 14 having extensible ends 15 are removably connected to the rear and side portions 16 and 17 respectively of the collar 12. The tracks support garment hangers 18 mounted thereon which may be slid outwardly upon the extensible ends to permit convenient access to the garments draped on the said hangers.

40 In the modified form shown in Fig. 3 the garment hanger track shown is indicated as non-removably fastened to the collar.

By constructing the collar of metal and in the manner shown the upper edge portion 45 of the wardrobe section is materially reinforced and strengthened and tracks, either of the fixed or of the removable type, may be easily connected thereto in a substantial manner. The metal collar furthermore lessens 50 the total weight and provides a firmer connection between the two trunk sections when the top cover which is hinged to the drawer section overlaps the collar of the wardrobe section.

55 While the metal collar is shown as forming part of a wardrobe trunk, it is to be understood that the collar may be used in connection with ordinary trunks without departing from the spirit and scope of the invention.

From the foregoing description it will be seen that a trunk collar construction is provided which is of very simple construction and is well adapted for the purpose described.

65

What I claim as my invention is:

1. The combination with a trunk, of a collar therefor consisting of a flat strip of material of greater strength than the walls of the trunk and shaped to conform to the 70 contour of the inner surface of an open portion of the trunk and to extend partly into said open portion and fastened thereto and to be overlapped by the cover of the trunk when said cover is in closed position, the 75 inner face of said collar extending in a plane outwardly.

2. The combination with a trunk, of a collar therefor consisting of a strip of metal shaped to conform to the contour of the 80 open portion of the trunk and to be connected to said open portion and to project outwardly therefrom and to be overlapped by the trunk cover when said cover is in closed position, and a garment hanger rail 85 connected at a plurality of points to said collar.

3. The combination with a trunk, of a collar therefor consisting of a U-shaped metal strip mounted within the trunk and projecting outwardly from the open end thereof to a position to be overlapped by the side flanges of the trunk cover when in closed position, and track members connected to three sides of the U-shaped strip.

4. The combination with a wardrobe trunk divided medially vertically into two sections and one of said sections having an upper open end, a U-shaped metal collar fastened to and projecting upwardly from the said 100 open end, and a top cover hinged to the trunk and positioned to close the open end and overlap portions of the U-shaped collar.

5. The combination with a wardrobe trunk divided medially vertically into two sections 105 and one of said sections having an upper open end, a U-shaped metal collar fastened to and projecting upwardly from the said open end, a top cover hinged to the trunk and positioned to close the open end and overlap portions of the U-shaped collar, and garment hanger rails connected to the rear and side portions of the U-shaped collar.

In testimony whereof, I affix my signature, in presence of two witnesses.

GEORGE HENRY WHEARY.

Witnesses:

ANNA M. NELSON,
GEORGE BENNISH.
